(57) **CLAIM**

The ornamental design for a tool for acting on a securement member of a digging tooth assembly, as shown and described.

DESCRIPTION

FIG. 1 is a perspective view a tool for acting on a securement member of a digging tooth assembly;

FIG. 2 is a front elevational view thereof; with the rear elevational view being a mirror image thereof;

FIG. 3 is a left side elevational view thereof; with the right side elevational view being a mirror image thereof;

FIG. 4 is a top plan view thereof; and,

FIG. 5 being a bottom plan view thereof.

The broken lines illustrated in FIGS. 1, 2 and 3 depict a portion of a handle for the illustrated tool but form no part of the claimed design.

1 Claim, 3 Drawing Sheets
